AUTOMOBILE SUN VISOR

Russell C. Huntoon, San Diego, Calif.

Application November 12, 1947, Serial No. 142,455

Term of patent 3½ years

(Cl. D14—6)

To all whom it may concern:

Be it known that I, Russell C. Huntoon, a citizen of the United States of America, residing at San Diego, in the county of San Diego and State of California, have invented a new, original, and ornamental Design for Automobile Sun Visor, of which the following is a specification, reference being had to the accompanying drawing, forming a part thereof.

Figure 1 is a perspective view of an automobile sun visor, showing my new design. Figure 2 is a sectional view thereof taken from the line 2—2 of Fig. 1, and omitting the side bracket showing my new design.

The dotted line showing in the drawing figures is for illustrative purposes only.

I claim:

The ornamental design for an automobile sun visor, as shown and described.

RUSSELL C. HUNTOON.
